UNITED STATES PATENT OFFICE.

EDWARD W. COOEY, DECEASED, LATE OF MALDEN, MASSACHUSETTS, BY MARY L. BRUNDAGE, ADMINISTRATRIX, OF MALDEN, MASSACHUSETTS.

ROTARY ENGINE.

Application filed April 18, 1922. Serial No. 555,355.

This invention relates to improvements in rotary engines such as described and shown in Letters Patent No. 723,242, granted to said Cooey, March 24, 1903, in which the 5 pistons are revolved around the engine shaft and at the same time reciprocate in a direction parallel to its axis; and these improvements consist particularly in the steam valves, their location and the means for 10 operating them, and in the construction and arrangement of the pistons.

In the engine of said Patent No. 723,242, the pistons were constructed so as to serve as steam valves to admit steam upon one 15 side of the central web and then upon the other; in the present construction the valves consist of sleeves or open cylinders which have a reciprocating sliding motion in chambers, preferably cylindrical in form, in the 20 hub of the rotary portion of the engine. These sleeves are operated by means of their connection with short levers at the ends of the engine, one end of each of such levers being pivoted to the interior of the hub of 25 the engine and the other end engaging a cam-groove around the interior of the caps, at the ends of the engine, which form a part of the steam chamber. These cam-grooves being so shaped that the sliding valve-sleeves 30 will be alternately moved in and then out so as to open and close the inlet ports from one end of the engine and the exhaust ports from the other end. In the construction shown in 35 the drawings, there are six of these sliding sleeve-valves, three to admit steam, operated from one end of the engine and three to control the exhaust, operated from the other end of the engine; these valves operate at the respective ends successively, one to admit steam and the next to exhaust it.

Three sets of sliding pistons operate in grooves in a central disc, or web, which is a part of the rotary portion of the engine, and these pistons are moved back and forth 45 through slots in the disc by the contact of their ends with the sinuous walls of the annular chamber formed by the cam faces of the stationary portion of the steam chamber. These pistons are formed of three or 50 more parts adapted to slide upon one another with suitable packing between them, so as to accommodate themselves to the curvature of the walls of the said annular chamber through which they move; the outer ones

running in grooves in both the outer cylindrical portion and the inner portion of the rotating part of the engine. The packing plate runs in a groove in the outer or peripheral part of this cylinder.

An oil pump is also provided at each end 60 of the engine, in which pistons of the character of those shown in Figure 2. of the drawings, are employed to draw in the oil and force it into the interior parts of the engine.

Referring to the drawings, forming a part of this specification: Figure 1 is a vertical longitudinal sectional view as though cut on line 1—1, Fig. 3; the engine shaft, the pump casing and the sleeve valves being in elevation; Figure 2 is a similar vertical section with the hub portion in which the sliding valves operate and a portion of the web in which the pistons slide, in elevation, and one of the three part pistons is in plan; 75 Figure 3 is a vertical cross-section of the engine on line 3—3, Fig. 1, and showing in elevation the steam supply pipe; Figure 4 is a vertical cross-section on line 4—4, Fig. 2, through one of the caps which close the ends 80 of the steam chamber, and in elevation, the levers which operate three of the sliding valves; Figure 5 is an enlarged cross-section of the pump, which is similar to the stationary portion B, of the steam chamber, as on 85 line 5—5, Fig. 2, viewed in a direction parallel with the shaft, and showing the face of such stationary portion which forms one side of the annular chamber, with ports cut in such curved walls at two sections to serve 90 as the inlet and outlet passages; Figure 6 is a cross-section on line 6—6, Fig. 5. The ring corresponding to B, is shown chambered for a considerable portion thereof in 95 two sections, into which the inlet and outlet ports are respectively cut. These Figures 5 and 6 are sectional views of modified forms of outlet and inlet ports.

Referring to the drawings by designating characters, A, is the outer cylinder or casing 100 and the stationary parts of the engine, the interior parts B, forming with the revolving disc D, and peripheral cylinder D', the steam expansion chamber in which the pistons P, operate. In the hub H, Fig. 2, is shown a 105 plan view of one of the three-part pistons, while in Fig. 3, a cross-sectional view of three of such pistons, made up of two outer plates

P, P and an intermediate packing plate P'. The bevelled ends of these pistons, which may be provided with anti-friction devices, bear against the curved faces like the parts 5 B, and move through the sinuous chamber I, formed thereby together with the disc D, and cylinder D', and at the same time slide back and forth in the slots in the disc D, by reason of the bearing of the ends of these 10 pistons against the curved faces of the parts B, thus increasing and then decreasing the area of the steam space between the disc D, and the walls of the parts B, as the engine rotates; the steam inlet and exhaust being 15 regulated by ports e, e' controlled by the sliding sleeve valves V. These valves are operated by levers L, pivoted at their inner ends at h, to the hub H, and their opposite ends, preferably provided with an 20 anti-friction roll, engage and run in a cam groove g formed between plates J, secured at the ends of the steam chamber and independently of the engine piston. These cam plates are capable of limited independent 25 rotational adjustment, to change the point of steam cut-off. The shape of these cam grooves is such as to cause the levers L, to swing in and out, and by means of the connecting rods U, pivoted to said levers and to 30 the respective sleeve valves, the latter are caused to slide in and out in their cylindrical chambers W, and thus open and close the steam inlet and exhaust ports e, e' at the proper intervals to apply pressure behind 35 the pistons P, and relieve the pressure in front of them as they revolve with the disc D. At the right of Fig. 3 is shown the steam supply pipe S, through which steam is admitted to the steam chamber S, C. A two 40 way valve in the pipe S, not shown, is employed, by which the supply of steam may be changed to reverse the engine. Oil may be supplied to the interior parts of the engine through pumps O, which in this case are 45 rotary pumps secured to the engine shaft E, S, within the caps C, at the ends of the steam chamber S, C; the pumps being constructed with pistons similar to those indicated as P, in Fig. 2, and with an annular chamber similar to the one I, shown in that figure. 50

Referring to Figs. 7 and 8; 7 is a sectional view of the oil pump on line 7-7 Fig. 8; and 8 is a section on line 8-8 of Fig. 7 in which the pistons P² corresponding to pistons P of the engine are revolved with the disc D² in a sinuous chamber I² similarly to the engine pistons. E, S is an extension of the engine shaft by which the pump-pistons are supported and revolved and which are 55 contained within the cylindrical shell O of Fig. 1. As the pistons P² are revolved, oil is drawn in through j and spring controlled valve k, to the chamber I', and as the pistons P² continue to revolve oil is forced out 60 through passages n and thence through pas-

sages m, to the engine and other parts to be lubricated. As soon as each piston P² passes an inlet valve IV, oil is drawn into the chamber I' behind it while the preceding piston is forcing the oil out through the outlet valve OV to the passages n, and thence to m in the main shaft and to other parts to be lubricated. 70

For use in such a pump, or in an engine which rotates in one direction only, instead of making the ports as e, e, through the peripheral surface of the cylindrical hub H, they may be made in the face of the cam surfaces at either side of the annular chamber I; a front elevation of one of which surfaces, looking in a direction parallel with the shaft, is shown in Fig. 5, e being the inlet port and e' the outlet. For the purposes of a pump these cams are made hollow or chambered, as illustrated in the sectional view Fig. 6, on line 6-6, Fig. 5. The same construction of chambered cams may be employed in a steam engine adapted to turn in one direction only, in which case the ports e, e, shown in Fig. 2, will be dispensed with and the ports e', e', shown in Fig. 5, will serve as outlet or exhaust ports. These ports are cut at an angle to the radii of the center of the shaft, so that the ends of the pistons P, will not enter the slots and catch therein as they pass. In all of the illustrations of the parts which are to be employed in a rotary pump, the dimensions may be made smaller, as the work to be done thereby is less severe. S, I, is the steam inlet to the chambered cam 100 and S, O, the exhaust pipe. Partitions as B', divide this chamber into two sections, one for inlet ports and the other for outlets. 95

From these pumps the oil is forced to the various interior parts of the engine through pipes m, Fig. 1, indicated in broken and full lines, partly through the center of the shaft E, S. The contact surfaces between the stationary and rotating parts of the engine are made steam tight by packing strips f and the film of oil. 105

The advantages of the improvements in the engine herein set forth are, that there are no dead centers; making the pistons in three or more parts, by which they are more easily and effectively packed to produce a steam-tight chamber; also placing the sliding steam valves in the inner parts of the rotary portion of the engine, near to the shaft, permits of better regulation of steam on account of the short steam passages from the valve chambers to the expansion chamber, and having less abrupt angles where the surfaces of the sinuous chamber change, permits of the use of a smaller sized engine with higher speed. Also constructing the cam-groove by which the sliding valves are actuated, of two similar plates, adds to the facility with which the parts may be assembled and arranged to control their adjustment, either by hand or 115 120 125 130

automatically to change the point for steam cut-off.

I claim:

In a rotary engine, an annular steam chamber, a rotating cylinder which forms the peripheral limit of that chamber, pistons which reciprocate across such chamber in a direction parallel to the engine shaft, two series of sliding valves in the rotary portion **5** of the engine, which valves also operate in a

direction parallel to said shaft; the valves of one series alternating in their action with those of the other and respectively are alternately operated by a cam at different ends of the engine, to open and close the valves **15** successively when the engine is in operation.

MARY L. BRUNDAGE,
Administratrix of Edward W. Cooey, deceased.
